UNITED STATES PATENT OFFICE.

ELI JOHN HYDE, OF SPOKANE, WASHINGTON.

TOOTH-BRUSH HOLDER.

No. 832,975.

Specification of Letters Patent.

Patented Oct. 9, 1906.

Application filed April 28, 1905. Serial No. 257,856.

To all whom it may concern:

Be it known that I, ELI JOHN HYDE, a citizen of the United States, and a resident of Spokane, in the county of Spokane and State 5 of Washington, have invented a new and Improved Tooth-Brush Holder, of which the following is a full, clear, and exact description.

The objects of this invention are to provide novel features for a tooth-brush holder that permit its attachment in a vertical position on a wall or the like, adapt it to completely incase a tooth-brush, afford a transparent side wall for exposure of the brush 10 while therein, afford spring-pressed end walls therefor that respectively serve as a lid and bottom for the holder and enable the convenient insertion and removal of the tooth-brush, provide drainage for the holder, 15 and also provide means for ventilation of the holder, so that the brush may dry quickly when held therein.

The invention consists in the novel construction and combination of parts, as is 20 hereinafter described, and defined in the appended claims.

Reference is to be had to the accompanying drawings, forming a part of this specification, in which similar characters of reference 25 indicate corresponding parts in all the figures.

Figure 1 is a perspective view of the improved tooth-brush holder in position on a wall, the lid of the holder being raised to permit a free insertion of a tooth-brush within the holder. Fig. 2 is a sectional view of the improved holder device, a tooth-brush therein, and the holder closed for protection of the brush; and Fig. 3 is a plan view of the device, 30 showing the lid thereof in closed adjustment.

The holder, as shown in the drawings, is in the form of a cylindrical wall or tube 5, preferably of glass, having suitable dimensions to adapt it to receive and hold a tooth-brush. The tubular wall 5 is inserted within a supporting-case 6, that may be of metal tubing or other available material and is secured therein, the case extending somewhat beyond each end of the holder-wall 5. The 45 case 6 is cut away at the front side, so as to expose the holder-wall, as shown at *a*, this opening leaving a portion of the case at each end imperforate. The case 6 is furnished with a plate-like back 7 for seated engagement with a wall *A* or other stable support whereon the brush-holder is to be secured,

and, as shown, the back plate 7 is extended at each end of the case 6 to permit the fixture of the complete holder device upon a support, such as the wall *A*, by means of screws *b* or *60* the like.

A closure 8 for each end of the case 6 is provided, these similar closures consisting of mainly circular plate-like lids having such a diameter as adapts them for seating upon the 65 respective ends of the case 6 and closing the same. Each lid or cover 8 is hinged upon the case 6 or the back plate 7, as shown at *c*, and is pressed upon the end of said case by a coiled spring *c'*, mounted upon the pintle of 70 the hinge and adapted for pressing down upon the lid, as is clearly shown for one lid in Fig. 3.

Near each end of the case 6 a plurality of spaced perforations *d* are formed therein, the 75 perforations in the normally lower end of the case-wall permitting drainage of the holder-case if an excess of water should be introduced therein with the tooth-brush. The perforations *d* in the upper end of the case 6, 80 with those in the lower portion of the same, permit air to enter within the case and pass therethrough, so that the brush will be dried by the air-current.

Upon each lid 8 a catch-lip *e* is formed that 85 projects from its edge at the front, these lips affording catches for manually opening the lids.

In use the owner of a tooth-brush *B* and the holder therefor first raises the upper lid 8 90 by pressure applied upon the catch-lip *e*, and when the lid is partially raised the end of the tooth-brush handle may be inserted and the entire brush be pushed into the holder by a single movement. When the brush is to be 95 removed for use, the catch-lip *e* on the lower lid 8 is depressed, which will permit the handle of the tooth-brush to drop through the opening into the hand of the one about to use it, whereupon a downward pull on the handle 100 will remove the tooth-brush, and the lid will instantly close the holder. The provision of the transparent cylindrical body or holder wall 5 and the opening in the opaque case 6 at its front side is very advantageous, as it 105 permits a free inspection of the tooth-brush held therein without removal of the same, and thus determine if the proper brush is in the holder.

By the use of the improved holder the 110 tooth-brush is kept clean and free from dust, is held separate from other brushes, and as

each box or holder may have an identifying-mark on it there will be an advantageous distinction afforded between brushes owned by different persons that may be guests or members of a family.

Having thus described my invention, I claim as new and desire to secure by Letters Patent—

1. A tooth-brush holder, comprising an elongated open-ended tubular casing provided with an opening intermediate of its ends at the front and with perforations adjacent to its ends, a hinged cover for each end of the casing, an open-ended tubular glass body within the casing and terminating short of the ends thereof, and an attaching-plate secured to the side of the casing opposite the cut-away portion and having its ends extending beyond the ends of the said casing.
2. A tooth-brush holder, comprising an elongated open-ended tubular casing pro-

vided with an opening intermediate of its ends at the front and with perforations adjacent to its ends, closures for the ends of the casing, and a tubular open-ended glass body 25 within the casing and terminating short of the ends of the said casing.

3. A tooth-brush holder, comprising an elongated tubular casing having closures for its ends and provided with means by which it may be secured to a support, the front of the casing being provided with an opening and a tubular glass body having open ends and secured within the casing with its ends terminating short of the ends of said casing. 30 35

In testimony whereof I have signed my name to this specification in the presence of two subscribing witnesses.

ELI JOHN HYDE.
